UNITED STATES PATENT OFFICE.

THOMAS M. NORTH, OF NEW YORK, N. Y., ASSIGNOR, BY DIRECT AND MESNE ASSIGNMENTS, TO ROBERT HOE AND CHARLES W. CARPENTER, OF NEW YORK, N. Y., COPARTNERS.

INKING MECHANISM FOR PRINTING-MACHINES.

SPECIFICATION forming part of Letters Patent No. 716,089, dated December 16, 1902.

Application filed March 1, 1900. Serial No. 6,938. (No model.)

To all whom it may concern:

Be it known that I, THOMAS M. NORTH, a subject of the Queen of Great Britain and Ireland, residing at New York, county of Kings, 5 and State of New York, have invented certain new and useful Improvements in Inking Mechanism for Printing-Machines, fully described and represented in the following specification and the accompanying drawings, forming a 10 part of the same.

This invention relates to certain improvements in inking mechanisms of printing-machines.

In order to successfully operate printing-machines, it is well understood that the ink must be thoroughly and intimately mixed, broken up, and distributed on the rollers of the inking mechanisms before it is applied to the forms. To accomplish this result, it has 15 been customary to allow the machines to run with the printing-couples in operation for a longer or shorter period of time, the impressions which are produced before the ink on the inking mechanisms is brought into the 20 proper condition being thrown away. If, however, the machine is allowed to run until the ink is brought into exactly the right condition, a considerable quantity of paper is 25 wasted.

One of the objects of this invention is to produce a printing-machine in which the printing mechanism and the inking mechanism are independently driven, so that it is possible to operate the inking mechanism to thoroughly break up and distribute the ink 30 through the several rollers thereof without running the remainder of the machine.

A further object of this invention is to produce a printing-machine employing a plurality of couples in which all the couples shall be driven from one train of mechanism and the inking mechanisms for the several couples shall be driven from another train of mechanism, so that it may be possible to operate 35 all the inking mechanisms of the machine for the purpose of inking up without driving any of the printing-couples.

A further object of the invention is to produce an improved form of inking mechanism

in which the form-rollers can be moved away 50 from the path of the form-carriers, so that they will not touch the forms during the process of inking up.

A further object of the invention is to produce a printing-machine employing a plurality of printing-couples and a plurality of inking mechanisms in which the couples are driven by one mechanism and the inking mechanisms by another mechanism, devices being provided of such a character that the 55 inking mechanism of any of the couples may be moved away from the path of the form-carrier of the couple.

A further object of the invention is to produce a printing-machine employing a plurality of printing-couples and a plurality of inking mechanisms in which the couples shall be driven from one mechanism and the inking mechanisms from another mechanism and in which by suitable connections it shall 60 be possible to simultaneously move the form-rollers of all the inking mechanisms away 65 from the path of the several form-carriers.

With these and other objects in view the invention consists in certain constructions and 70 in certain parts, improvements, and combinations, as will be fully described in the following specification and then specifically pointed out in the claims hereunto appended.

In the accompanying drawings, which form 80 a part of this specification, and in which like characters of reference indicate the same parts, Figure 1 is a sectional side elevation of the machine, taken on the line 1 1 of Fig. 2 and looking in the direction of the arrow in 85 that figure. Fig. 2 is a plan view, a portion of the frame being shown in section. Fig. 3 is a vertical cross-section on the line 3 3 of Fig. 1. Fig. 4 is a detail side elevation of the two end couples of the machine, illustrating 90 more particularly the means for moving the inking-rollers away from the form-cylinders.

The machine which has been selected to illustrate a concrete embodiment of the invention is a rotary multicolor-machine, preferably printing from planographic surfaces and adapted to print one color on one side of the web and two colors on the other side. It 95

is to be understood, however, that the invention is not limited to multicolor-machines nor to machines employing planographic surfaces.

5 Referring to said drawings, 1 and 2 indicate the usual side frames, in which the several shafts of the machine are journaled, the bearings for the shafts being of any usual or desired form. The couple which prints upon 10 one side of the web is shown at the left-hand end of the machine, said couple consisting of a form-cylinder 3, mounted on a shaft 4, and an impression-cylinder 5, mounted on a shaft 6. After being acted upon by this couple the 15 web passes around the surface of a large impression-cylinder 7, mounted on a shaft 8. In the machine shown a plurality of form-cylinders coöperate with this large impression-cylinder 7, and while any number of such 20 cylinders may be employed in the present construction two such cylinders are shown—a form-cylinder 9, mounted on a shaft 10, and a form-cylinder 11, mounted on a shaft 12.

In machines constructed in accordance with 25 the invention independent driving mechanisms are provided for the printing-couples and the inking mechanisms. While the driving mechanism for the printing-couples may be variously constructed and arranged, in the 30 present machine a power-shaft 13 is provided, said shaft being provided with any suitable driving device—as, for instance, a belt-pulley 14. This shaft 13 extends from side to side of the machine and is journaled in suitable bearings in the machine-frame. It carries on the end opposite the pulley a gear 15, said gear being secured to the shaft in any suitable manner, as by a key 16. The gear 15 meshes with a gear 17, said gear being secured 35 in any suitable manner, as by a key 18, to a counter-shaft 19, which also extends through the machine from side to side and is parallel with the power-shaft 13. The counter-shaft 19 is extended through the side 40 frame 1 and carries on its projecting end a gear 20, said gear being arranged to run loosely on the shaft 19, but being capable of being secured thereto in any suitable manner. While the construction by which the 45 gear 20 is secured to the shaft may be varied, in the machine herein shown the hub 21 of the gear 20 forms a part of a clutch, the co-operating part consisting of a notched sliding collar 22, which is secured to the shaft 19 by a feather 23 or in any other suitable manner. As is usual in such constructions the sliding 50 collar 22 is provided with a groove 24, which is engaged by pins 25, said pins being carried on a yoke 26. This yoke 26 has an upward extension 27, which forms a handle, and a lower extension 28, (see Fig. 3,) which is pivoted, by means of a pin 29, between ears 30, secured to the under side of the side frame 1. The gear 20 meshes with a gear 31, which is secured to 55 the cylinder-shaft 8 in any suitable manner, as by a key 32. The gear 31 meshes with a

gear 33, which is secured to the shaft 12 in any suitable manner, as by a key 34. The gear 31 also meshes with a gear similar to the gear 33, which is secured to the shaft 10. This 70 gear is not, however, shown in any of the figures, it being located directly under the gear 33 and is of the same size as said gear. The gear 31 further meshes with a gear 35, which is secured, by means of a key 36 or in any other suitable manner, to the shaft 6 of the impression-cylinder 5. The gear 35 meshes with a gear 37, which is secured by a key 38 or in any other suitable manner to the shaft 4 of the form-cylinder 3. 80

From the construction so far described it is obvious that when power is applied to the main shaft, as by a belt, and the clutch-collar 22 is in engagement with the hub 21 of the gear 20 the power-shaft will drive the members of 85 the several couples through the train of gearing which has been described. When, however, the clutch-collar is disengaged or thrown into the position shown in Fig. 2, the power-shaft will rotate without rotating the 90 members of the couples, since the gear 20, which is loose on the shaft 19 and which serves as the transmitting-gear from this shaft to the train, will not be rotated by the shaft. 95

As has been before stated, an independent mechanism is provided for driving the inking mechanisms which supply ink to the several couples. While this driving mechanism may be variously constructed and arranged, 100 in the machine shown the gear 17, which has been before described as keyed to the shaft 19, is arranged to mesh with a large gear 39, which is loosely mounted on the shaft 8 of the large impression-cylinder 7, the construction 105 being clearly shown in Fig. 1. The gear 39 meshes with two gears 40 and 41, mounted on the shafts 10 and 12, respectively, and also with a gear 42, mounted on the shaft 6. The gear 42 meshes with a gear 43, mounted on 110 the shaft 4, before referred to. The gears 40, 41, and 43 run loosely on the shafts 10, 12, and 4, respectively, and it may be here remarked that while it is convenient to mount these gears on the shafts in the manner described they might be mounted in any other suitable manner—as, for instance, on studs projecting from the sides of the frame—the object being to provide a train of gearing for driving the inking mechanisms which is independent of that which drives the printing-couples. 115

As has been stated, the purpose of the gears 40, 41, and 43 is to provide a driving mechanism for the inking devices to be hereinafter described. While these gears may be arranged to drive the inking devices in any suitable manner, in the construction shown the gear 40 has secured thereto a gear 44, said gear being shown as slightly less in 120 diameter than the gear 40 and being secured thereto by bolts 45. In the same manner 125

the gear 41 has a similar gear 46 secured to it by bolts 47, and the gear 43 has a similar gear 48 secured to it by bolts 49.

Three groups of inking mechanisms are shown, one for each of the form-cylinders 3, 9, and 11. These inking mechanisms may be of any usual or desired construction. In the machine shown they comprise fountains 50, provided with fountain-rolls 51. The ink is delivered from these fountain-rolls 51 by means of ductors 52—the operating mechanisms of which are not shown, as they may be of any ordinary form—to distributing-rolls 53. Coöoperating with the rolls 53 are groups of rolls 54, these rolls serving to mix, break up, and distribute the ink in the ordinary manner. The rolls 53 are driven rolls, the shafts of these rolls being provided with gears 55, which mesh with intermediates 56, which are mounted on studs 57, extending from the side frames 2. These intermediates 56 mesh with the gears 44, 46, and 48, respectively, the rolls 53 being driven in the manner described to drive the rolls 54 by friction, as is common in such constructions.

Coöoperating with the rolls 53 are transmitting-rolls 58, of which two are shown, these rolls serving to distribute the ink from the rolls 53 to auxiliary distributing-rolls 59, of which two are shown. These rolls 59 are mounted on shafts 60, which are journaled in the side frames, and these shafts 60 are provided at one end with gears 61, said gears meshing with intermediates 62, which are mounted on studs projecting from the side frames 2. The intermediates 62 are in mesh with the gears 44, 46, and 48. It is apparent, therefore, that the rolls 59 are driven rolls. Each of these rolls 59 delivers its ink to a group of form-rollers, of which two (marked 63 and 64) are shown, these rollers being mounted on shafts 65 66, respectively.

Each group of form-rollers 63 64 is mounted so as to be movable toward and away from the path of movement of the forms and will in the construction shown be held away from the said path of movement until the "inking-up" operation is completed. While the rollers may be mounted and located in various ways so as to effect this result, preferably and as in the machine shown the shaft 65 is mounted in bearings 67, which are carried on blocks 68. These blocks 68 are mounted on projections 69, which are secured to, preferably by being formed in one piece with, arms 70, the said arms being supported on the shafts 60 of the distributing-rolls 59. In the same manner the shaft 66 of the rollers 64 are mounted in bearings 71, said bearings being mounted on blocks 72. These blocks 72 are secured to projections 73, which are secured to, preferably by being formed in one piece with, arms 74, which are also mounted on the shafts 60. The blocks 68 and 72 are preferably adjustably secured to the projections 69 and 71, this being effected in any suitable manner. In the construction shown each

block is provided with a slot 75, through which passes a bolt 76, the construction being a usual one.

It will of course be understood that there are two of the arms 70—one at each side of the machine—and two of the arms 74—one at each side of the machine—and it will be further seen that by swinging the arms 70 74 around the shafts 60 as centers the form-rollers 63 64 will be moved toward and away from the path of travel of the forms on the form-cylinders and that this movement will be effected without moving the rollers 63 64 out of contact with the rolls 59.

Any suitable means may be employed to give the arms 70 74 the swinging movement referred to. In the machine shown two disks 77 are provided for each couple, one of these 85 disks being located on each side of the machine for controlling the movement of the arms 70 74 of one of the group of form-rollers 63 64, and two cam-disks 78 are provided—one on each side of the machine—for controlling the movement of the arms 70 74 of the other group of form-rollers. The disks 77 are mounted on studs 79, projecting from the side frames of the machine, and the disks 78 are mounted on studs 80, similarly supported. 95 Each of these disks 77 78 is provided with two eccentric or cam slots 81 82, these slots being engaged by pins or rollers 83 84, carried on the arms 70 74, respectively. It is apparent, therefore, that the disks constitute 100 cams and that by rotating them the arms 70 74 will be moved about the shafts 60 as centers, and the rollers 63 64 will be given the swinging movement before referred to.

Any suitable means may be provided for 105 giving the disks the rotating movement before referred to, which, it may be remarked, is preferably, though not necessarily, a simultaneous movement. While the means by which this simultaneous movement may be 110 given to all the sets of disks may be varied widely, in the machine shown each of the disks 77 is provided with a segment 85 and each of the disks 78 with a segment 86. Each pair of disks 77 78 is arranged to mesh with 115 a movable segment. Three such segments are provided on each side of the machine, these segments being marked 87 88 89. The segments 87 have projecting from them arms 90, and the segments 88 have projecting from 120 them arms 91 92, and the segments 89 have projecting from them arms 93. The arms 91 of the segments 88 have connected to them links 94, said links being provided with hooked ends 95, which take over pins 96 on the arms 125 90, so that the two arms are connected for simultaneous movement. The hooks 95 are closed, however, by pins 97, and when said pins are withdrawn the hooks will be released, so as to disconnect the segments 87 88. 130 The arms 92 are connected to the arms 93 by means of links 98, said links having hooked ends 99, closed by pins 100, which take over pins 101 on the arms 92. With the construc-

tion as described it is apparent that when the connecting-links 94 98 are engaged with the arms 90 92 a movement of any pair of the three pairs of segments 87 88 89 will move the other two pairs of segments and operate the disks so as to produce a movement of the form-rollers of each inking mechanism either in or out, as the case may be.

Any suitable means may be provided for moving either pair of disks. Preferably, however, and as in the machine shown there is provided a shaft 102, which extends across the machine from side to side and is provided at each end with segments 103, said segments meshing with segments 104. These segments 104 are in the construction shown connected to the segments 88. The shaft 102 is further provided with handle-sockets 105 on each side of the machine, to which sockets are connected handles 106. With this construction it is apparent that by moving either of the handles 106 the form-rollers of each inking mechanism may be moved toward or away from the path of the forms carried on the form-cylinder.

It may happen under certain circumstances that it is desirable to disconnect the inking mechanism of any one of the couples from that of the other couples and to operate said inking mechanism separately. To this end each of the segments 87 is provided with a handle 107, one of these handles being of course located on each side of the machine. In the same way the segments 88 are provided with handles 108, and the segments 89 are provided with handles 109. If, for instance, it is desired to operate the inking mechanism which is controlled by the segment 87 independently of the other mechanisms the links 94 are disconnected from the pins 96, thus disconnecting the segments 87 from the remaining segments. By operating handles 107 either simultaneously or independently the inking mechanism for that couple will be thrown out.

The operation of the machine will be readily understood without further description.

It is to be understood that the mechanisms by which the invention is carried into effect may be widely varied. The invention is not, therefore, to be limited to the specific details of construction hereinabove described.

What I claim is—

1. In a printing-machine, the combination with a power-shaft, of a plurality of printing-couples, gearing by which the printing-couples are driven from the power-shaft, a plurality of inking mechanisms, gearing by which the inking mechanisms are driven from the power-shaft, and means for disconnecting a member of the printing-couple gearing so that the members of the couples may be stationary without disconnecting the inking mechanisms from their driving-gearing, substantially as described.

2. In a printing-machine, the combination with a power-shaft, of a plurality of shafts

carrying the members of a plurality of printing-couples, a plurality of gears fast on the shafts, gearing by which said shafts are driven from the power-shaft, a plurality of inking mechanisms, a plurality of gears loose on the printing-couple shafts, said gears operating to drive the inking mechanisms, and gearing by which said gears are driven from the power-shaft, substantially as described.

3. In a printing-machine, the combination with a power-shaft, of a plurality of shafts carrying the members of a plurality of printing-couples, a plurality of gears fast on the shafts, gearing by which said shafts are driven from the power-shaft, means for disconnecting said gearing, a plurality of inking mechanisms, a plurality of gears loose on the printing-couple shafts, said gears operating to drive the inking mechanisms, and gearing by which said gears are driven from the power-shaft, substantially as described.

4. In a printing-machine, the combination with a power-shaft, of a plurality of shafts carrying the members of a plurality of printing-couples, a counter-shaft, a gear whereby said shaft is driven from the power-shaft, a plurality of inking mechanisms, a plurality of gears loose on the printing-couple shafts, said gears being driven from the gear on the counter-shaft and operating to drive the inking mechanisms, a loose gear on the counter-shaft, a plurality of gears fast on the printing-couple shafts, said gears being driven from said loose gear, and means for securing the loose gear to and disconnecting it from the counter-shaft, substantially as described.

5. In a printing-machine, the combination with a form-carrier, of an inking mechanism, means for driving the form-carrier, means independent of the form-carrier-driving means for driving the inking mechanism, means for disconnecting the form-carrier from its driving means, means for moving the form-rollers of the inking mechanism toward and away from the path of the form-carrier without disconnecting the inking mechanism from its driving means, substantially as described.

6. In a printing-machine, the combination with a form-cylinder, of an inking mechanism, means for driving the form-cylinder, a gear driven independently of the form-carrier-driving means for driving the inking mechanism, and means for moving the form-rollers of the inking mechanism away from the path of the form-cylinder and holding them away during the operation of inking up without disconnecting the inking mechanism from its driving means, substantially as described.

7. In a printing-machine, the combination with a form-cylinder, of an inking mechanism, means for driving the cylinder, a gear driven independently of the form-carrier-driving means for driving the inking mechanism, means independent of the form-cylinder-driving means for driving the gear, means for disconnecting the form-cylinder from its driv-

ing means, and means for moving the inking mechanism toward and away from the path of the form-cylinder without disconnecting the inking mechanism from its driving means, substantially as described.

8. In a printing-machine, the combination with a form-cylinder, of a shaft on which it is mounted, means for driving the shaft, an inking mechanism, a gear loose on the shaft of the form-cylinder operating to drive the inking mechanism, means independent of the form-cylinder-driving means for driving said gear, and means for moving the form-rollers of the inking mechanism toward and away from the form-cylinder without disconnecting the inking mechanism from its driving means, substantially as described.

9. In a printing-machine, the combination with a form-cylinder, of a shaft on which it is mounted, means for driving the shaft, means for disconnecting the shaft from its driving means, an inking mechanism, a gear loose on the shaft of the form-cylinder operating to drive the inking mechanism, means independent of the form-cylinder-driving means for driving said gear, and means for moving the form-rollers of the inking mechanism toward and away from the form-cylinder without disconnecting the inking mechanism from its driving means, substantially as described.

10. In a printing-machine, the combination with a plurality of printing-couples, gearing by which they are driven, a plurality of inking mechanisms, gearing by which the inking mechanisms are driven, means for disconnecting the gearing which drives the printing-couples without disconnecting the gearing which drives the inking mechanisms, and means for moving the form-rollers toward and away from the path of the form-carriers without disconnecting the inking mechanisms from the driving-gearing, substantially as described.

11. In a printing-machine, the combination with a form-cylinder, of a distributing-roll, a gear from which said roll is driven, a plurality of auxiliary distributing-rolls driven from the same gear, form-rollers for transmitting the ink from the auxiliary distributing-rolls to the forms, and means for moving the form-rollers away from the path of the form-cylinder and holding them away during the operation of inking up without disconnecting the distributing-rolls from the driving-gear, substantially as described.

12. In a printing-machine, the combination with a form-cylinder, of a distributing-roll, a gear from which said roll is driven, a plurality of auxiliary distributing-rolls driven from the same gear, a plurality of form-rollers cooperating with each auxiliary distributing-roll and driven therefrom, and means for moving the form-rollers toward and away from the path of the form-cylinder without disconnecting any of the driving connections, substantially as described.

13. In a printing-machine, the combination

with a form-cylinder, of a gear loose on the shaft of said cylinder, means for driving the gear, a distributing-roll driven from said gear, a plurality of auxiliary distributing-rolls also driven from said gear, a plurality of form-rollers coöperating with each auxiliary distributing-roll and frictionally driven therefrom, and means for moving the form-rollers toward and away from the path of the form-cylinder without moving them out of contact with the auxiliary distributing-rolls, substantially as described.

14. In a printing-machine, the combination with a plurality of form-carriers, of a plurality of inking mechanisms each including a distributing-roll, a shaft on which said roll is mounted, arms pivoted on said shaft, form-rollers, the shafts of which are mounted in said arms, and means for simultaneously moving the arms of all the inking mechanisms about the distributing-roll shafts, substantially as described.

15. In a printing-machine, the combination with a form-carrier, of an inking mechanism including a distributing-roll, a shaft on which said roll is mounted, arms pivoted on said shaft, form-rollers, the shafts of which are mounted in said arms, and normally stationary means for simultaneously moving the arms in opposite directions about their shaft as a center, substantially as described.

16. In a printing-machine, the combination with a form-carrier, of an inking mechanism including a distributing-roll, a shaft on which said roll is mounted, arms pivoted on said shaft, form-rollers, the shafts of which are mounted in said arms, normally stationary cams, and means whereby the cams may be rotated to simultaneously move the arms in opposite directions about their shaft as a center, substantially as described.

17. In a printing-machine, the combination with a form-carrier, of an inking mechanism including a distributing-roll, a shaft on which said roll is mounted, arms pivoted on said shaft, form-rollers, the shafts of which are mounted in said arms, and rotating slotted cams for simultaneously moving the arms in opposite directions about their shaft as a center, substantially as described.

18. In a printing-machine, the combination with a form-carrier, of an inking mechanism including a distributing-roll and a plurality of auxiliary distributing-rolls, shafts on which the distributing-rolls are mounted, means for driving the shafts, arms mounted on the shafts of the auxiliary distributing-rolls, form-rollers, the shafts of which are mounted in said arms, and means for simultaneously moving the arms so as to carry the form-rollers away from the path of the form-carrier, substantially as described.

19. In a printing-machine, the combination with a form-carrier, of an inking mechanism including a distributing-roll and a plurality of auxiliary distributing-rolls, shafts on which the distributing-rolls are mounted, means for

driving the shafts, arms mounted on the shafts of the auxiliary distributing-rolls, form-rollers, the shafts of which are mounted in said arms, rotating slotted cams for moving the arms, and means for simultaneously rotating the cams, substantially as described.

20. In a printing-machine, the combination with a plurality of printing-couples, of a plurality of inking mechanisms, each mechanism including a distributing-roll and a plurality of auxiliary distributing-rolls, shafts on which the distributing-rolls are mounted, means for driving the shafts, arms carried by the shafts of the distributing-rolls, form-rollers, the shafts of which are mounted in the arms, and means for simultaneously operating the arms of all the inking mechanisms so as to move the form-rollers toward and away from the path of the form-carriers of the printing-couples, substantially as described.

21. In a printing-machine, the combination with a plurality of printing-couples, of means for driving the couples, means for disconnecting the couples from the driving means, a plurality of inking mechanisms, means for driving the inking mechanisms independently of the printing-couples, and means for moving the form-rollers of all the inking mechanisms toward and away from the form-carriers of the couples without disconnecting the driving connections of the inking mechanisms, substantially as described.

22. In a printing-machine, the combination with a plurality of printing-couples, of means for driving the couples, means for disconnecting the couples from the driving means, a plurality of inking mechanisms, means for driving the inking mechanisms independently of the printing-couples, and means for simultaneously moving the form-rollers of all the inking mechanisms toward and away from the form-carriers of the couples without disconnecting the driving connections of the inking mechanisms, substantially as described.

23. In a printing-machine, the combination with a plurality of printing-couples, of a plurality of inking mechanisms, means for driving the printing-couples, means for disconnecting the couples from their driving means, means for driving the inking mechanisms, means for moving the form-rollers of each of the inking mechanisms toward and away from the path of the form-carriers of the couples, and connections between the moving means of the several inking mechanisms, substantially as described.

24. In a printing-machine, the combination with a plurality of printing-couples, of a plurality of inking mechanisms, means for driving the printing-couples, means for disconnecting the couples from their driving means, means for driving the inking mechanisms, means for moving the form-rollers of each of the inking mechanisms toward and away from the path of the form-carriers of the couples, and disconnectible connections between the

moving means of the several inking mechanisms, substantially as described.

25. In a printing-machine, the combination with a plurality of printing-couples, of a plurality of inking mechanisms, a power-shaft, a train of gearing on one side of the machine operating to drive the printing-couples, said train being driven from the power-shaft, means for disconnecting said train from the power-shaft, and a train of gearing on the other side of the machine operating to drive the inking mechanisms, said gearing being driven from the power-shaft, substantially as described.

26. In a printing-machine, the combination with a plurality of printing-couples, of a power-shaft, a train of gearing on one side of the machine by which the printing-couples are driven from the power-shaft, means for disconnecting a member of the train, a plurality of inking mechanisms, a train of gearing on the other side of the machine by which the inking mechanisms are driven from the power-shaft, and means for moving the form-rollers of the inking mechanisms toward and away from the path of the form-carriers of the printing-couples without disconnecting the inking-mechanism train, substantially as described.

27. In a printing-machine, the combination with a plurality of printing-couples, of a power-shaft, a train of gearing on one side of the machine by which the printing-couples are driven from the power-shaft, means for disconnecting a member of the train, a plurality of inking mechanisms, a train of gearing on the other side of the machine by which the inking mechanisms are driven from the power-shaft, and means lying on both sides of the machine for moving the form-rollers of the inking mechanisms toward and away from the path of the form-carriers of the printing-couples without disconnecting the inking-mechanism train, substantially as described.

28. In a printing-machine, the combination with a plurality of printing-couples, of a power-shaft, a train of gearing on one side of the machine by which the printing-couples are driven from the power-shaft, means for disconnecting a member of the train, a plurality of inking mechanisms, a train of gearing on the other side of the machine by which the inking mechanisms are driven from the power-shaft, and means lying on both sides of the machine and operable from each side for moving the form-rollers of the inking mechanisms toward and away from the path of the form-carriers of the printing-couples without disconnecting the inking-mechanism train, substantially as described.

29. In a printing-machine, the combination with a plurality of printing-couples, of a plurality of inking mechanisms, means for driving the couples, independent means for driving the inking mechanisms, means for mov-

ing the form-rollers of the inking mechanisms toward and away from the path of the form-carriers of the couples, a shaft extending across the machine, connections between said shaft and all the form-roller-moving means, and means for operating the shaft, substantially as described.

30. In a printing-machine, the combination with a plurality of printing-couples, of a plurality of inking mechanisms, each including a distributing-roll, auxiliary distributing-rolls and form-rollers, shafts on which the distributing-rolls are mounted, means for driving said shafts, arms mounted on the 10 shafts of the auxiliary distributing-rolls, said arms serving to support the shafts of the form-rollers, rotating cams for moving said arms about the auxiliary-roll shafts, means for operating the rotating cams of each couple, a 15 shaft extending across the machine, connections between said shaft and the means for rotating the cams of each couple, and means for rotating the shaft, substantially as described.

31. In a printing-machine, the combination with a printing-couple, of an inking mechanism including a distributing-roll and a plurality of auxiliary distributing-rolls, shafts on which the distributing-rolls are mounted, 20 means for driving the shafts, arms supported on each end of the auxiliary-distributing-roll shafts, form-rollers, the shafts of which are mounted in said arms, rotating cams on each side of the machine for operating the 25 arms, and means on each side of the machine for rotating the cams, substantially as described.

32. In a printing-machine, the combination with a plurality of printing-couples, of a plurality of inking mechanisms, said inking mechanisms each including a distributing-roll, auxiliary distributing-rolls and form-rollers, a power-shaft, a train of gearing driven from the power-shaft lying on one side of the 40 machine for driving the printing-couples, means for disconnecting said train of gearing from the power-shaft, a train of gearing lying on the other side of the machine driven from the power-shaft for driving the inking mechanisms, arms supported on the shafts of the auxiliary distributing-rolls and carrying the form-roller shafts, and means for simultaneously moving the arms of all the couples so as to move the form-rollers toward and away from 45 the path of the form-carriers of the printing-couples, substantially as described.

33. In a printing-machine, the combination with a plurality of printing-couples, of a plurality of inking mechanisms, said inking mechanisms each including a distributing-roll, auxiliary distributing-rolls and form-rollers, 50

a power-shaft, a train of gearing driven from the power-shaft lying on one side of the machine for driving the printing-couples, means for disconnecting said train of gearing from the power-shaft, a train of gearing lying on the other side of the machine driven from the power-shaft for driving the inking mechanisms, arms supported on the shafts of the auxiliary rolls and carrying the form-roller shafts, 55 rotating cams for moving the arms of all the inking mechanisms, and means for simultaneously rotating the cams, substantially as described.

34. In a printing-machine, the combination with a plurality of printing-couples, of a plurality of inking mechanisms, said inking mechanisms each including a distributing-roll, auxiliary distributing-rolls and form-rollers, a power-shaft, a train of gearing driven from the power-shaft lying on one side of the machine for driving the printing-couples, means for disconnecting said train of gearing from the power-shaft, a train of gearing lying on the other side of the machine driven from the power-shaft for driving the inking mechanisms, arms supported on the shafts of the auxiliary distributing-rolls and carrying the form-roller shafts, rotating cams for moving the arms, an operating device for the cams of each inking mechanism, and connections between the operating devices of the several inking mechanisms, substantially as described.

35. In a printing-machine, the combination with a plurality of printing-couples, of a plurality of inking mechanisms, said inking mechanisms each including a distributing-roll, auxiliary distributing-rolls and form-rollers, a power-shaft, a train of gearing driven from the power-shaft lying on one side of the machine for driving the printing-couples, means for disconnecting said train of gearing from the power-shaft, a train of gearing lying on the other side of the machine driven from the power-shaft for driving the inking mechanisms, arms supported on the shafts of the auxiliary distributing-rolls and carrying the form-roller shafts, rotating cams for moving the arms, a device for operating the cams of each inking mechanism, connections between the rotating cams of all the inking mechanisms, a shaft, and means carried by the shaft for moving the operating device of one inking mechanism, substantially as described.

In testimony whereof I have hereunto set my hand in the presence of two subscribing witnesses.

THOMAS M. NORTH.
